DESIGN FOR A TELEPHONE RECEIVER

Nathan A. Kurman, Long Island City, N. Y., assignor to Kurman Electric Co., Inc., New York, N. Y.

Application June 24, 1936, Serial No. 63,457

Term of patent 14 years

To all whom it may concern:

Be it known that I, Nathan A. Kurman, a citizen of the United States, residing at 4323 40th Street, Long Island City, in the county of Queens and State of New York, have invented a new, original, and ornamental Design for Telephone Receivers, of which the following is a specification, reference being had to the accompanying drawing, forming part thereof.

I claim:

The ornamental design for a telephone receiver, as shown.

NATHAN A. KURMAN.
